IMPLEMENT OF WARFARE

Vicente Gonzales, Chicago, Ill.

Application August 22, 1933, Serial No. 686,278

1 Claim. (Cl. 89—37)

This invention relates to certain new and useful improvements in implements of warfare, and more particularly to mounts for guns within armored cars or tanks for broadcast fire and for anti-aircraft use.

One of the principal objects of the invention contemplates the use of a mounting which will readily permit and facilitate the altering of the gun position for active use as an infantry weapon as well as an anti-aircraft gun.

The invention consists in the novel combination and arrangement of parts to be hereinafter described and claimed.

In the drawing:

15 Fig. 1 is a top plan view of an armored car or tank with the top partly broken away showing the relative arrangement of the guns and mounts therefor within the confines of the vehicle;

20 Fig. 2 is a sectional view taken on line 2—2 of Fig. 1;

Fig. 3 is a perspective view of the gun and mountings therefor;

Fig. 4 is a vertical sectional view taken on line 4—4 of Fig. 3; and

25 Fig. 5 is a sectional view taken on line 5—5 of Fig. 4.

Referring to the drawing in detail wherein like characters of reference denote corresponding parts, the reference character 10 indicates generally the chassis of a motorized armored car or tank which is provided with communicating openings 11 in the sides and top thereof to facilitate manipulation and use of the fire-arm in a manner to be presently apparent. The armored car or tank forms no part of the present device, but is described and illustrated for purposes of illustration in bringing out the novel characteristics of the present device.

40 The gun mounting or support alluded to in the foregoing contemplates the employment of standards 12 having base portions 13 and braces

14 extending from remote portions of the base to appropriate points in the height of the standards. Cross members 15 and 16 are employed at intervals between the base portions, braces, and standards and which may be suitably anchored to the floor within the armored car or tank in order to maintain the supports in position as against vibration and weaving motions of the armored car or tank incident to the rough terrain over which the vehicle travels.

5 A supporting plate or gun mount 17 carries ears 18 pivotally associated with the standards 12. The said supporting plate or gun mount is provided with an opening 19 for the passage of a pivot bolt 20 carried by the firearm 21, which 15 as before stated may be in the nature of a machine gun or anti-aircraft weapon. A second bolt 22 carried by the firearm 21, in spaced relation to the bolt 20, is designed for sliding motion within an arcuate-shaped slot 23 in the 20 plate in order that transverse or broadcast sweeping motion may be imparted to the gun.

From the foregoing description and accompanying drawing it is readily noted that the firearm may be shifted to occupy the several distinct positions as shown in full and dotted lines in Figs. 2, 4, and 5 of the drawing.

Having thus described my invention what is claimed as:

30 A device of the type described comprising two spaced upright members, a supporting plate, said supporting plate having its ends bent to provide arms having pivots, said supports having openings for loosely receiving said pivots, said supporting plate having an opening, a firearm having a pivot arranged within said opening, said plate having a curved opening, and a reach carried by said firearm and extending through said opening and having means arranged to press against one side of the plate to connect the fire- 40 arm in fixed relation with the plate.

VICENTE GONZALES.
